UNITED STATES PATENT OFFICE

168,659

COMBINED DESK AND SEAT UNIT

Rudolph J. Silverman, Highland Park, Ill.

Application August 23, 1951, Serial No. 16,412

Term of patent 3½ years

(Cl. D33—11)

To all whom it may concern:

Be it known that I, Rudolph J. Silverman, a citizen of the United States, residing at Highland Park, in the county of Lake and State of Illinois, have invented a new, original, and ornamental Design for a Combined Desk and Seat Unit, of which the following is a specification, reference being had to the accompanying drawing forming a part thereof.

In the drawing:

Figure 1 is a perspective view of a combined desk and seat unit, showing my new design, with the pivoted desk top of the book pan in slightly raised position;

Figure 2 is a fragmentary detail section taken on the line 2—2 of Figure 1 to show the curling to the outside of the upper edge of the book pan; and

Figure 3 is a fragmentary detail section taken on the line 3—3 of Figure 1 to show the folding of the steel edges of the back rest members.

The characteristic features of my design for the unit disclosed reside in the base portions having the configurations as shown.

I claim:

The ornamental design for combined desk and seat unit, substantially as shown and described.

RUDOLPH J. SILVERMAN.
